UNITED STATES PATENT OFFICE.

JOHN HENRY BALMER, OF MAPLEWOOD, NEW JERSEY, ASSIGNOR TO J. H. BALMER CO., OF NEWARK, NEW JERSEY, A CORPORATION OF NEW JERSEY.

DESIGN FOR A COMBINED SOAP HOLDER AND GRAB RAIL.

Application filed April 8, 1925. Serial No. 13,067. Term of patent 14 years.

To all whom it may concern:

Be it known that I, JOHN HENRY BALMER, a citizen of the United States, and resident of Maplewood, in the county of Essex and State of New Jersey, have invented a new, original, and ornamental Design for a Combined Soap Holder and Grab Rail, of which the following is a specification.

Reference is had to the accompanying drawing in which the figure is a perspective view of a soap holder and grab rail embodying the design.

I claim:

The ornamental design for a combined soap holder and grab rail as shown.

JOHN HENRY BALMER.
